UNITED STATES PATENT OFFICE.

JOSEPH WILLIAM ROBINSON, OF AURORA, ILLINOIS, ASSIGNOR TO HARRY G. DALTON AND FRANK R. DALTON, OF AURORA, ILLINOIS.

DEVICE FOR KEEPING BOILERS CLEAN.

SPECIFICATION forming part of Letters Patent No. 744,619, dated November 17, 1903.

Application filed May 22, 1903. Serial No. 158,250. (No model.)

To all whom it may concern:

Be it known that I, JOSEPH WILLIAM ROBINSON, of Aurora, in the county of Kane and State of Illinois, have invented certain new and useful Improvements in Devices for Keeping Boilers Clean; and I do hereby declare that the following is a full, clear, and exact description thereof, reference being had to the accompanying drawings, and to the letters of reference marked thereon, which form a part of this specification.

This invention relates to improvements in devices for preventing accumulation of scale and mud deposits in the bottoms of boilers; and the invention consists in the matters hereinafter set forth, and more particularly pointed out in the appended claims.

In the drawings, Figure 1 is a fragmentary perspective view, partially broken away, of a boiler, showing the application of my improvements thereto. Fig. 2 is a partial transverse section of the boiler and my improved cleaning device. Fig. 3 is a top plan view of the device removed from the boiler. Fig. 4 is a side elevation of said cleaning device. Fig. 5 is a transverse section taken on line 5-5 of Fig. 3.

As shown in said drawings, A designates the boiler, B B the flues thereof, and B' the base of the smoke-stack through which the products of combustion are discharged after passing through the flues.

C C designate a plurality of troughs open at their top and closed at their ends. Said troughs are arranged longitudinally in said boiler and side by side in parallel relation. Said troughs are preferably V-shaped in cross-section, and they are supported in the bottom of the boiler a distance above the crown-sheet on legs or standards D D at the front and rear ends of the group of troughs. As herein shown, three troughs are employed, and they are joined to form a unitary structure by means of tie-bars E, extending transversely over and across said group of troughs, one located at each end of the group and one at the middle thereof. Said tie-bars are rigidly connected with the troughs by means of V-shaped strips C', which are fitted and secured to the inner faces of the side walls of the troughs, and the upper ends of said strips

are bent inwardly toward each other and overlap and are secured to the tie-bars.

The legs or standards D are made of such length as to hold the troughs above the sphere 55 of the most violent agitation of the water, which is in the immediate vicinity of the crown-sheet of the boiler, and said troughs are at all times submerged in the water in the boiler, so that they are always filled with 60 water. The troughs are held from being forced upwardly by the violent ebullition of the water beneath the same from the position which they are intended to occupy by means of a transverse brace-bar F, located over one 65 end of the group of troughs and connected therewith, the cross-bar fitting against the lower sides of the lowermost line of tubes B. As herein shown, the brace-bar F is formed integral with the legs or standards D at the 70 front end of the group of troughs, said legs or standards and the brace-bar being made of a single piece of metal bent in inverted-U form and the upper or closed end of the device constituting said brace-bar. 75

In order to facilitate the insertion and removal of the device into and from the boiler, the front and rear legs or standards D are hinged to the side walls of the outermost troughs in a manner to swing upwardly at 80 the side of the troughs, and said legs are connected by a connecting-bar G, which is pivoted or loosely connected at its ends with said legs, whereby the legs at both ends of the group of troughs are swung on their 85 hinges simultaneously. As the brace-bar F is connected rigidly with the forward legs D, it is thrown downwardly in front of the group of troughs when the legs are thrown upwardly, as shown in dotted lines in Fig. 4. Said legs 90 D and connecting-bars G constitute, in effect, a collapsible supporting-frame for the troughs, and the parts are locked in their supporting positions by means of brace-rods H, which are loosely connected with the intermediate tie-bar E and are provided at their forward ends with hooks which fit in sockets in the brace-bar F. When said legs are thus swung upwardly at the sides of the troughs and the brace-bar swung downwardly in front 100 of the same, said troughs may be removed from the boiler through a manhole or hand-

hole A' of dimensions slightly greater than the width and height of the group of troughs. Said troughs may be made of a length to extend from one end to the other of said boiler, 5 or two or more groups of troughs may be employed arranged end to end. The latter arrangement is herein shown.

The apparatus described operates to collect sedimentary matter in the water and prevent 10 the same from falling on or accumulating in the form of incrustation or deposit on the crown-sheet, and the mode of operation of the device to effect this result is as follows: The troughs, as before stated, are located below the level of the water, and inasmuch as they are held above the sphere of the most violent agitation or ebullition of the water in the immediate vicinity of the crown-sheet the bodies of water contained in said troughs 15 are in a comparatively quiescent state. The agitation or ebullition of the water occurring just above the crown-sheet throws upwardly between the troughs strong currents, which carry with them sedimentary matter—such as magnesia, lime, and mud—held in suspension 20 in the water. As such currents approach the surface of the water they become weaker and lose their force or power to carry the sedimentary matter contained therein, so that 25 the sedimentary matter is released and drops downwardly. Owing to the presence of ascending currents of water between the adjacent troughs, the sediment thus released from the weakened upper currents will not fall 30 back through the spaces between said troughs, but will be deflected toward the less-agitated zones, or spheres, which are located immediately above the relatively quiet bodies of water contained in the troughs. The sediment 35 is therefore in this manner directed to the troughs and settles to the bottom thereof, and when the troughs become filled or partially filled they are removed from the boiler through the hand or man hole A' in the manner described, cleansed of such accumulation, and returned to their places.

The troughs C may be supported in the boiler in any suitable manner so long as the substantial relation shown is preserved. The 40 V-shape form of the troughs in cross-section is a desirable one for the reason that such form offers a minimum resistance or impediment to the ascending currents of water, while at the same time affording wide receiving-mouths for the troughs to collect the sediment falling from the weakened upper currents.

I claim as my invention—

1. An apparatus for preventing the accumulation of sediment in the bottom of a boiler comprising a plurality of troughs of V shape in cross-section, the wide, open sides of which are directed upwardly, said troughs being located side by side with spaces between the 55 same, and a frame for supporting said troughs and made of such height that the troughs are located below the plane of the longitudinal

axis of the boiler, and means for preventing the troughs from rising.

2. An apparatus for preventing the accumulation of sediment in the bottom of a boiler comprising a plurality of upwardly-opening troughs, a frame for supporting said troughs and connecting said troughs in a manner to constitute a unitary structure, said frame being made collapsible so as to be folded.

3. An apparatus for preventing the accumulation of sediment in the bottom of a boiler comprising a plurality of upwardly-opening troughs and a folding frame for supporting 80 said troughs above the crown-sheet of the boiler and below the water-line thereof, said troughs being located side by side and separated by spaces.

4. An apparatus for preventing the accumulation of sediment in the bottom of a boiler comprising a plurality of upwardly-opening troughs, of V shape in cross-section, and a supporting-frame connecting said troughs side by side with spaces between the same, 90 said frame being constructed to hold the troughs just above the crown-sheet of the boiler and means for preventing said frame from rising comprising a part on said frame adapted to engage the boiler-flues.

5. The combination with a tubular boiler, the flues of which are discontinued a distance above the crown-sheet of the boiler, of a plurality of upwardly-opening V-shaped troughs located between the crown-sheet and said flues, and a frame for supporting said troughs above the crown-sheet of the boiler and constructed to permit said troughs and the frame to be removed as a unitary structure from the boiler through a suitably-located opening 105 therein.

6. A device for preventing the accumulation of sediment in the bottom of a boiler comprising a plurality of upwardly-opening troughs adapted to be supported side by side 110 with spaces between the same in the boiler, means for connecting the troughs to constitute a unitary structure, and legs or standards for supporting the group of troughs above the crown-sheet of the boiler, said legs or 115 standards being hinged to the troughs and being loosely connected by rigid bars.

7. A device for preventing the accumulation of sediment in the bottom of a boiler comprising a plurality of upwardly-opening 120 troughs adapted to be supported side by side in the boiler, means for connecting said troughs to constitute a unitary structure, legs or standards for supporting the group of troughs above the crown-sheet of the boiler 125 and means for preventing said troughs from rising in the boiler.

8. An apparatus for preventing the accumulation of sediment in the bottom of a boiler comprising a plurality of upwardly-opening 130 troughs arranged side by side and separated by spaces, legs or standards hinged to the said troughs, and a brace-bar connected with the legs or standards at one end of the group

of troughs and adapted to engage the lower line of the flues of the boiler.

9. An apparatus for preventing the accumulation of sediment in the bottom of a boiler comprising a plurality of upwardly-opening troughs arranged side by side and separated by spaces, transverse tie-bars connecting said troughs, front and rear legs hinged to the troughs, connecting-bars, one at each side of the group of troughs, for connecting the corresponding front and rear legs, a transverse brace-bar connected with the front legs and

adapted to engage the lower line of flues, and a brace-rod hinged to one of said tie-bars and adapted for detachable connection with said brace-bar. 15

In testimony that I claim the foregoing as my invention I affix my signature, in presence of two witnesses, this 18th day of May, A. D. 1903.

JOSEPH WILLIAM ROBINSON.
